FABRIC DRAWOFF MEANS FOR TEXTILE MACHINES

Emil William Kaul, Wyomissing, Pa., assignor to
Textile Machine Works, Wyomissing, Pa., a
corporation of Pennsylvania

Application April 1, 1942, Serial No. 437,100

15 Claims. (Cl. 66—149)

This invention relates to the fabric draw-off means of textile machines, such as straight or full-fashioned knitting machines and the like, which employ rod members for drawing folded fabrics or welts from the loop-forming mechanism thereof.

Rods have long been satisfactorily employed to connect folded welts of stockings to the fabric draw-off means of straight or full-fashioned hosiery knitting machines. Such rods have been found unsatisfactory in certain respects when used on machines equipped with automatic or semi-automatic welt mechanisms of the type hereinafter referred to, which are provided with guide channels for the rods. A difficulty experienced is that in such installations the rod ends are subjected to excessive wear, thereby decreasing the efficiency and reliability of the fabric draw-off means.

One object of my invention is to provide novel fabric draw-off means for knitting machines and the like, which overcomes the mentioned and other difficulties.

Another object is to provide an improved fabric draw-off rod particularly adapted for use on full-fashioned knitting machines provided with certain automatic or semi-automatic welt mechanisms.

A further object is to provide an improved welt rod for full-fashioned knitting machines having end portions of special wear-resistant properties.

It is also an object to provide an improved welt rod for full-fashioned knitting machines comprising portions of different wear resistant properties.

A further object is to provide an improved rod of the type adapted for use as a welt rod for full-fashioned knitting machines and the like comprising a main body or central section, and interchangeable end parts.

With these and other objects in view, which will become apparent from the following detailed description of the illustrative embodiment of my invention shown in the accompanying drawings, the invention resides in the novel rod construction and fabric draw-off means comprising the new elements, features of construction and arrangement of parts in cooperative relationship as herein disclosed, and hereinafter more particularly pointed out in the claims.

In the drawings:

Figure 1 is a top view of part of a full-fashioned knitting machine showing my invention in operation;

Fig. 2 is a sectional view taken substantially along the line 2—2 of Fig. 1;

Fig. 3 is a view showing a welt rod of the invention;

5 Fig. 4 is an enlarged detail view of a replaceable welt rod end portion constructed in accordance with my invention;

Fig. 5 is an enlarged sectional view taken substantially along the line 5—5 of Fig. 2, certain parts being broken away;

10 Fig. 6 is a fragmentary view of a solid welt rod portion constructed in accordance with my invention;

Fig. 7 is a view showing part of the rod of Fig. 15 6 provided with a replaceable end portion; and

Fig. 8 is a view similar to Fig. 7 showing another modification of the invention.

In the drawings and description, only those parts of a knitting machine necessary to a complete understanding of the invention, are presented; further information as to the construction and operation of other related, usual and well known knitting elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

20 2. Three catalogues entitled—The “Reading” Full-Fashioned Knitting Machines Parts Catalog—published and copyrighted by the Textile Machine Works, in 1929, 1935 and 1940, respectively.

3. Booklet entitled—The “Reading” High Production Full-Fashioned Knitting Machine—which forms a supplement to the above noted 1940 parts catalog of the Textile Machine Works, and which booklet is a publication of the Textile Machine Works, and was copyrighted by the latter in 1940.

4. Pamphlet entitled—Knitting Machine Lectures—published by the Wyomissing Polytechnic Institute, Wyomissing, Pennsylvania, in 1935.

45 In Figs. 1 and 2 of the drawings are shown parts of one knitting section of a multi-section straight or full-fashioned “legger” knitting machine which operate in customary manner to produce knitted fabric, and to tension and draw such fabric from the knitting instrumentalities and wind it on take-up means as it is produced. Such knitting mechanism is of well known construction and comprises in general a bank of needles 16 arranged uprightly in parallel regularly spaced relationship in a needle bar 12 which

50 55

is operated in well known manner so that the needles 10 thereof cooperate with sinkers and dividers generally indicated at 13 and knockover bits 14 of a sinker-head unit 15 to produce knitted fabric "S" from yarn fed to said implements in well known manner and by usual means (not shown).

To produce a knitted fabric having a substantially uniform loop formation throughout, tension is applied to the fabric as it is knitted. This is effected by means of usual fabric draw-off or take-up mechanism (Figs. 1 and 2) which comprises in general spaced members or bridges 16 fastened to a table or front bed 17 as by screws 18, on which the fabric connecting means, such as welt bar 19 and welt or draw-off rod 20 are supported for movement therealong. The welt bars 19 and the welt rods 20 are connected to draw-off bands or straps 22 and 23 as by connector members 22a and 23a, respectively, and are moved along the bridges 16 by respective take-up reels, the reel for straps 23 being shown at 24. The reels for straps 22 are not shown, but are in general similar to reels 24. The take-up reels 24 are fastened to a shaft 25 mounted for rotation in bearing brackets such as 26 secured to a usual presser shaft (not shown) which is provided to move the needles 10 toward and from the sinker head unit 15. This connection of the fabric to both the needles 10 and the take-up reel 24, both of which are simultaneously moved toward and from the sinkerhead 15 by the presser shaft, reciprocates the fabric connector parts, such as the welt rod 20, relative to the stationary rod support members 16. This reciprocatory sliding action of the rod 20 on its supports, combined with its movement therealong effected by the winding of connector bands 23 on the reel 24, causes such wear as may result to be concentrated on the rod ends.

In prior art full-fashioned knitting machines where it is customary to manually and independently place each welt bar 19 into position for the hooks 19a thereof to receive the sinker and divider loops of the starting course of each fabric in each knitting section, the top surfaces of the bridges are used to support the welt bars throughout their entire operative cycle, after which the same surfaces of the bridges are utilized to support the welt rods throughout their operative cycle until sufficient fabric has been knitted to permit the rods 20 to ride from the bridges 16 and be wrapped on the take-up reel 24. In such cases the welt bars 19 are placed on the table or front bed 17 and are there inactively positioned so as not to interfere with the operation of the welt rods 20. Inasmuch as the top surfaces of the bridges 16 are thus used to support the welt bars 19 and the welt rods 20 at different times, the full width of each of the bridges 16 is utilized as a bearing surface for said members. Wear incident to such sliding of the rod on the bridges is, consequently, distributed over each rod end for a distance corresponding to the full bridge width.

On those machines, however, where means is provided, as in the case of semi-automatic welt mechanisms herein illustrated, for simultaneously moving all of the welt bars 19 into position to receive the loops of the starting course of each fabric, the welt bars 19, in addition to being supported by the bridges 16 when in operation, are also mounted on the bridges 16 while inactive, i. e., during the entire operative cycle of the welt rods 20. Consequently, since the top surfaces of

the bridges 16 can not be used to support and guide the welt rods 20 in such machines, the opposed side portions of cooperating bridges 16 are grooved as at 21 to receive and guide the rod ends therein. The welt rods are thus moved in a plane below the welt bars and above the table as shown in Figs. 1, 2 and 5.

The mechanism herein illustrated for simultaneously advancing a plurality of welt bars 19 into loop receiving position, comprises in general a shaft 28 which extends lengthwise of the machine and which is rotatably mounted in bearings 29 fastened to the front bed or table 17 as by bolts 30. By turning the shaft 28 counterclockwise from the position of Fig. 2, arms 31, which are secured to the shaft 28 and which are pivotally connected to links 32, thrust studs or travellers 33 on the free ends of links 32 against wear plates 34 fastened to the welt bar 19, thereby advancing the bars 19 toward the sinkerhead 15 so that projections 19b on bars 19 come into engagement with lugs 35 extending from the bridges 16 (Fig. 1). The bands or straps 22 which draw the welt bars from the needles in a draw-off direction also function to bias the combined positioning and wear plates 34 of the welt bars into yielding engagement with travellers 33 during movement of the bars toward the needles, as well as when the bars are inactively positioned as is shown in Figs. 1 and 2. The travel of the studs 33, upon turning of the shaft 28, is confined to a path parallel to the bridges 16 so as to remain in operative position relative to the plates 34 on bar 19, by means of guide brackets 36 which are carried thereby and whose angle portions 37 (Fig. 1) slide in groove portions 38 arranged parallel to the upper surfaces of the bridges 16.

In order that all of the welt bars 19 may be in position to start another series of welts immediately after the welts have been turned, the bars are placed on the bridges 16 as in Figs. 1 and 2 after loops of the starting course have been transferred to the needles, and are there held by means of the tension applied to the straps 22 by the take-up means (not shown). Since, as previously indicated, the welt bars 19 are kept on the bridges 16 while the welt rods are being used to tension and draw the fabric from the needles, and since the top surfaces of the bridges 16 cannot be used to support the welt rods in mechanisms of the type herein set forth, the surface available for such use is considerably less than hitherto; this will be apparent from a comparison of the width of the bearing surface provided by the grooves 21 with the full width of the bridges 16. A combination of various factors, such as the reduced bearing surface provided for the welt rods on machines of the type mentioned and the high speeds at which these machines are operated, results in the rod ends being worn down more rapidly than heretofore.

To provide a welt rod particularly adapted for use with welt mechanisms of the type above explained, the present invention comprises an improved rod construction having replaceable end portions whose wear resisting characteristics enable said end portions to resist the additional wear placed thereon because of the reduced bearing surface and the higher speed operation of the mechanisms associated therewith as compared with prior devices.

One such construction as shown in the drawings comprises a rod 20 having a main body portion 20a of uniform tubular construction

throughout adapted to receive replaceable wear resistant rod ends or insert portions 21, see Fig. 5. These inserts 21 are preferably formed of material embodying relatively high wear resistant properties compared to the intermediate portions of the rod, such as hardened steel. To facilitate securing of the rod ends 21 to the hollow body portion 20a, each rod end 21 is preferably shouldered at 21a as shown, thereby forming cylindrical portions 21b and 21c of different diameters, the heavier or bearing portion 21b being adapted to slide in the groove portions 27 of the bridges 16, whereas the portion 21c is inserted into an end of the hollow body portion 20a and secured thereto as by a press fit, soldering, or some other known manner. The different parts of the rod are so constructed that when assembled there will be no gaps between the rod ends and the main body portion, whereas the bearing portion 21b of each rod end 21 is of the same diameter as the body portion 20a. The completed rod 20 will accordingly in effect have an unbroken surface and will be of uniform diameter throughout, so as to reduce the likelihood of the fabric becoming engaged or pinched thereon.

This invention may also be applied to a welt rod of solid cross section as is shown by the modified forms of the invention illustrated in Figs. 6, 7 and 8, which forms particularly adapt themselves to the rebuilding of solid rods of the type heretofore generally used on machines not equipped with automatic or semi-automatic welt mechanism, for use on machines so equipped. To provide a solid rod with replaceable end portions, the ends 40a and 41a of rods 40 and 41 are shaped to receive replaceable end portions such as a cap member 42 and a sleeve or collar member 43, respectively. Such members may be slipped over the rod ends and fastened thereto in the same manner as previously indicated in connection with the end portions 21, members 42 and 43 also, of course, being preferably formed of hardened steel or other material having good wear resistant properties.

To facilitate assembly of the cap member 42 on the rod end 40a, an opening 42a is provided which acts as a vent through which to exhaust the air which is trapped in the interior of the cap as the latter is slipped over and fastened to said rod end.

The provision of replaceable end portions in a rod of the type herein set forth makes it possible to provide a rod having fabric-receiving and bearing portions constructed of different materials best adapted for their respective uses, and also provides simple means for extending the life of the rods themselves, inasmuch as the rod ends, which are the portions subject to the most wear, can be readily replaced when desired.

Of course, the improved fabric draw-off means can be changed and modified in various ways without departing from the invention herein disclosed and hereinafter claimed.

I claim:

1. A welt rod for full-fashioned knitting machines having wear resisting portions at its ends and an intermediate portion having separable socketed connections with said wear resisting portions.

2. A welt rod comprising a hollow mid-section and wear resisting end portions having separable socketed connections with said hollow section.

3. A welt rod comprising an element having reduced end sections and wear resisting sleeve

members separably mounted on said reduced sections of the same diameter as the non-reduced portion of the element.

4. A welt rod comprising an element having reduced end portions and wear resisting caps separably mounted on said reduced portions and of the same diameter as the non-reduced portion of the element.

5. In a textile machine, fabric draw-off means comprising a pair of parallel horizontally arranged support members, a take-up reel, strap members attached to said reel and having rod connecting means attached to their free ends, and a rod member for connecting a folded hem of fabric to said connecting means and comprising a fabric engaging portion and cylindrical hardened replaceable end portion arranged to slide along said supports.

6. In a textile machine, fabric draw-off means comprising a pair of parallel horizontally arranged support members, a take-up reel, strap members attached to said reel and having rod connecting means attached to their free ends, and a rod member for connecting a folded hem of fabric to said connecting means and comprising a hollow fabric engaging portion and solid replaceable end pieces fastened in the ends of said hollow portion and arranged to guide said rod along said support members.

7. In a textile machine, fabric draw-off means comprising a pair of parallel horizontally arranged support members, a take-up reel, strap members attached to said reel and having rod connecting means attached to their free ends, and a rod member for connecting a folded hem of fabric to said connecting means and comprising a solid fabric engaging portion having the ends thereof provided with cylindrical hardened replaceable end pieces for guiding said rod along said support members.

8. In a textile machine, fabric draw-off means comprising a pair of parallel horizontally arranged support members, a take-up reel, strap members attached to said reel and having rod connecting means attached to their free ends, and a rod member for connecting a folded hem of fabric to said connecting means and comprising a solid fabric engaging part having reduced end portions and separately formed rod end pieces adapted to be slipped over and secured to said end portions for guiding said rod along said support members.

9. In a textile machine, fabric draw-off means comprising a pair of parallel horizontally arranged support members, a take-up reel, strap members attached to said reel and having rod connecting means attached to their free ends, and a rod member for connecting a folded hem of fabric to said connecting means and comprising a solid fabric engaging part having reduced end portions, and separately formed cap pieces adapted to be slipped over and secured to said end portions for guiding said rod along said support members.

10. A welt rod having separable cylindrical hardened portions at its ends for increasing the resistance to wear.

11. In a textile machine, the combination of a pair of parallel supporting elements, a welt rod mounted to travel on said elements, said rod having cylindrical hardened separable portions at its ends adapted to increase its resistance to wear.

12. A welt rod comprising a hollow mid-section, reduced portions on said mid-section, and

wear resistant end portions relatively larger than said reduced portions and separably associated with said mid-section.

13. A welt rod comprising an element having reduced end sections and wear resisting sleeve members separably mounted on said reduced sections.

14. A fabric draw-off for full-fashioned knitting machines comprising parallel supporting elements having opposed channel grooves, and a draw-off rod moving in said grooves having separable hardened cylindrical end portions

more wear resistant than the intermediate portion of the rod and arranged to permit contact with all the surfaces of said grooves.

15. In a textile machine, the combination of a pair of parallel horizontally arranged support members having grooves in their facing sides, and a welt rod having replaceable wear resisting end portions mounted in said grooves, said end portions having substantially the same dimension transverse to said grooves as the intermediate portion of said rod.

EMIL WILLIAM KAUL.
